BRICK BENCH

Donald J. Dirkse, Midland, Mich., assignor to The Dow Chemical Company, Midland, Mich., a corporation of Delaware

Filed Mar. 26, 1965, Ser. No. 84,710

Term of patent 14 years

(Cl. D15—11)

Fig. 1

Fig. 2

This application is a continuation-in-part of my copending application Serial No. D. 74,387, filed April 10, 1963, now abandoned.

I claim:

The ornamental design for a brick bench, substantially as shown and described.
